[57] CLAIM

The ornamental design for an enclosure for holding volcanic ash or imitation briquets in a barbecue grill, as shown and described.

DESCRIPTION

FIG. 1 is a perspective view of the enclosure for holding volcanic ash or imitation briquets in a barbecue grill showing my new design;

FIG. 2 is a front elevational view thereof; the rear elevational view being a mirror image of the view shown in this Figure;

FIG. 3 is a right end elevational view thereof;

FIG. 4 is a left end elevational view thereof;

FIG. 5 is a top plan view thereof; and,

FIG. 6 is a bottom plan view thereof.
